UNITED STATES PATENT OFFICE.

INGENUIN HECHENBLEIKNER, OF CHARLOTTE, NORTH CAROLINA, ASSIGNOR TO SOUTHERN ELECTRO CHEMICAL COMPANY, OF NEW YORK, N. Y., A CORPORATION OF NEW JERSEY.

ELECTRIC FURNACE.

1,173,960.

Specification of Letters Patent.

Patented Feb. 29, 1916.

Application filed November 2, 1914. Serial No. 869,830.

To all whom it may concern:

Be it known that I, INGENUIN HECHENBLEIKNER, a subject of the Emperor of Austria, residing at Charlotte, in the State of 5 North Carolina, United States of America, have invented certain new and useful Improvements in Electric Furnaces, of which the following is a specification.

This invention relates to improvements in 10 electric furnaces and especially to such as are adapted for treatment of phosphate rock to expel phosphoric acid, and the objects of the invention are to overcome the peculiar difficulties usually found present in treating 15 phosphate rock and the slag formed therefrom in the electric furnace, and it consists essentially of the improved construction and arrangement of parts hereinafter described in detail in the accompanying specification 20 and drawings.

In the drawings, Figure 1 is a vertical section through an embodiment of the invention partially in elevation. Fig. 2 is a side elevation. Fig. 3 is a plan view. Fig. 25 4 is a sectional detail through the manhole. Fig. 5 is a detail, being the side view of the electrode clamp. Fig. 6 is an end view of the electrode clamp. Fig. 7 is a sectional detail of the electrode support. Fig. 8 is a 30 sectional detail of the bottom tap hole on the furnace. Fig. 9 is a cross sectional detail of the upper or slag tap hole. Fig. 10 is a detail in elevation of feeding mechanism. Fig. 11 is an elevation of the feeding 35 device.

Like characters of reference refer to like parts in all the figures.

The electric furnace itself may, in the present invention, be said to consist of three 40 parts comprising the bottom section A, the tapered stack section B and the outlet elbow C. These parts are detachably connected and fit together, the detachable connection between the bottom portion and tapered 45 stack section being effected by abutting channel sections 10 and 11 which are bolted or otherwise clamped together while the detachable connection between the tapered stack section and the elbow section is effected 50 by similar channel steel sections 12 and 13 which are similarly connected together. The bottom section A is water-cooled and is, in fact, practically in the form of a water jacket, being formed with inner and outer 55 walls 14 and 15 of thin sheet metal separated

and connected together by I-beams 16 or the like and having means for circulating water in the interior and distributing the same equally therethrough.

To effect an even distribution of water, 60 an annular outlet channel 17 is formed around the top on the exterior into which equally distributed overflow pipes 18 are arranged to discharge, such overflow pipes extending in a radial direction from the interior of the water jacket. The inflowing water is adapted to pass through a conduit 65 19 which opens at the top of the water jacket.

The furnace is originally constructed 70 without any lining in the bottom section whatever. The water jacket, however, being considerably cooler than the slag formed within the furnace will cause a portion of the slag to freeze to the inner wall of the 75 water jacket to thereby form a lining D of frozen slag. It is found that a lining of this character is the only one which will resist the action of the calcium silicate slag. It is impracticable to use any form of firebrick 80 or other lining generally used in electric furnaces, owing to the fact that such lining will be readily attacked by the phosphoric acid and calcium silicate slag. The body portion 85 rests on suitable transverse bearing 20 conveniently formed of wood or like insulating material. On one side of the body portion a slag overflow E is provided which is kept open during the operation and which is so arranged that the molten slag seals the furnace. This slag overflow includes a 90 U-shaped hollow water cooled member 22 which extends upwardly in an inclined direction from the slag outlet 23 formed in the body portion and is provided with a 95 curved water cooled mouth 24 as shown in Fig. 9, the member 22 being suitably fastened to the exterior of the water jacket. Suitable manholes 25 are also formed around the body portion having water cooled doors 100 26, the inner sides of the water cooled doors being covered with a layer 27 of frozen slag.

The tapered section B of the furnace is not water-cooled and is adapted to carry the 105 electrodes F which extend in an inclined direction through it. The electrodes are each surrounded by a water cooled holder 30 mounted in projections 31 formed on the side of the tapered portion. Each electrode 110

is adapted to be adjusted and regulated in position manually or automatically through the medium of water cooled electrode clamps G which are mounted on trolleys H which run on suitable tracks I.

5 The clamps G each comprise a pair of semi-circular hinged clamping members 32 and 33 each hinged to a bracket 34 which is secured to the trolley H. These clamps are 10 hollow and water cooled and may be connected together at their lower extremities by a tightening bolt 36 which extends through lugs 37 and 38 in each of the semi-circular clamps.

15 The track I is conveniently in the form of an I-beam and the trolley H is provided on opposite sides with a plurality of trolley wheels 39, the diameter of which is such as to substantially fill the distance between the 20 flanges of the I-beam I. The current connection for each electrode may be made by flexible current conductors 40 which are connected to the sides of the clamps G. To provide for the changing of electrodes, a 25 plurality of stirrups 41 are provided at intervals on the track I adapted to hang in position so that they may conveniently support the electrodes which are to be inserted to be used to replace the one which has been 30 withdrawn. The tracks I may be braced by suitable beams 42 which connect the track with the top of the tapered section. The elbow section C is adapted to discharge the furnace gases in a lateral direction and also 35 carries a feeding means. This feeding means is adapted to distribute the material to be treated in a uniform manner and includes a hopper 45 from the bottom of which two diverging conduits 46 and 47 extend 40 which finally discharge into opposite sides of the elbow section a short distance above its juncture with the tapered section. A suitable sliding gate 48 may be provided to control the feeding of material. Both the 45 tapered section and the elbow section are conveniently covered with a suitable insulating means such as a layer of asbestos 49 held in position by a suitable layer of sheet metal 50.

50 In practically using the invention in the manufacture of phosphoric anhydrid from which phosphoric acid may be made, suitable quantities of natural phosphate rock, siliceous material and carbon are mixed together and fed to the electric furnace. An alternating current is preferably used. The heat of the arc and the resistance heat developed within the furnace will expel phosphoric acid and phosphorous vapor from the furnace mixture, leaving a calcium silicate slag 55 which as it accumulates will overflow through the slag overflow E. The phosphorous and phosphoric anhydrid expelled from the furnace gases will be suitably oxidized and caught by suitable absorption 60 means, such for example as those shown in 65

my United States Patent Number 1,112,211, granted on September 29th, 1914. The walls of the body portion will be effectively protected from the action of the slag and phosphoric acid by the layer of molten slag 70 which will form on it.

It will be observed that the tapered portion of the furnace is a considerable distance above the electrodes and above the reaction zone whereby the gases liberated by the reaction will uniformly preheat that portion of the charge which is in the tapered portion and stack of the furnace. It will also be observed that as the heat of the furnace gases is reduced the area over which the air 80 is distributed is also reduced whereby a uniform degree of heating is obtained and the flow of the furnace gases is not restricted by the reduction of the area. Further it will be observed that as the electrodes extend 85 through the smooth inclined body portion of the furnace wall no pocket will be formed above the electrodes in which hot gases might collect to overheat either the electrodes, the feeding mixture or the wall of 90 the furnace.

It is essential for the commercial advantages of this process in the manufacturing of phosphorous or phosphoric acid, that the temperature be well regulated and the immense heat of the electric arc be so applied as to prevent a local overheating of the charge or the slag. Overheating of the charge or slag will cause a distillation of not only phosphorus but will also procure the 100 distillation of silicium and silicium compounds. Silicium and silicium compounds are mostly the cause for "killing" the phosphorus or in case the phosphorus is oxidized afterward for the manufacturing of phosphoric acid, said phosphoric acid is forming water insoluble, commercially worthless compounds from SiO_2 and P_2O_5 . To prevent this disadvantage in the process the typical 105 design of the furnace is the most important 110 feature.

Tests have shown that in the case of this furnace the charge is moving regularly and under a steady pressure downward between and around the electrodes. In this way the 115 once melted and reduced slag is removed quickly out of the dangerous arc zone before overheating can take place. Fresh material replacing quickly the melted slag prevents the formation of hollow spaces between the 120 electrodes and charge, and at the same time preventing the overheating of material and distillation of silicium and silicium compounds. It doesn't make any difference if the material is powdered, granulated or briqueted, provided the melting of the material is made as described above no distillation of 125 harmful compounds will take place.

As many changes could be made in the above construction and many apparently 130

widely different embodiments of my invention, within the scope of the claims, constructed without departing from the spirit or scope thereof, it is intended that all matter contained in the accompanying specification and drawings should be considered as illustrative only.

What I claim as my invention is:

1. In an electric furnace, a track, a trolley mounted thereon, water cooled hinged clamping members depending from the trolley and adapted to engage an electrode.
- 10 2. In an electric furnace, a track, a trolley mounted thereon, water cooled hinged clamping members depending from the trol-

ley and adapted to engage an electrode, and stirrup members mounted on the track adapted to support an electrode.

3. In an electric furnace, a track, a trolley mounted thereon, electrode supporting means 20 depending from the trolley, and a plurality of stirrups supported independently of the trolley and adapted to temporarily support the electrode during change of electrodes.

In witness whereof I have hereunto set my 25 hand in the presence of two witnesses.

INGENUIN HECHENBLEIKNER.
